UNITED STATES PATENT OFFICE

SAMUEL L. HIRSHEY, OF CASTORLAND, NEW YORK.

SECTIONAL EXPANDING DRUM.

1,173,967.

Specification of Letters Patent. Patented Feb. 29, 1916.

Application filed August 27, 1915. Serial No. 47,669.

To all whom it may concern:

Be it known that I, SAMUEL L. HIRSHEY, a citizen of the United States, residing at Castorland, in the county of Lewis and State 5 of New York, have invented certain new and useful Improvements in Sectional Expanding Drums; and I do hereby declare the following to be a full, clear, and exact description of the invention, such as will enable 10 others skilled in the art to which it appertains to make and use the same, reference being had to the accompanying drawings, and to the letters and figures of reference marked thereon, which form a part of this specification. 15

This invention relates to new and useful improvements in drums for use in making cylindrical fiber boxes and comprises essentially an expanding cylinder made up of a 20 series of rods spaced apart and secured to the heads of the drum of the cylinder, the drum being made of sections and adapted to be expanded by a cam upon a rock shaft.

The invention comprises a simple and efficient apparatus of this nature having various details of construction, combinations and arrangements of parts which will be hereinafter fully described, shown in the accompanying drawings and then specifically defined in the appended claims. 30

My invention is illustrated in the accompanying drawings, in which:

Figure 1 is an end view of an expanding cylinder made in accordance with my invention. Fig. 2 is a vertical longitudinal sectional view through the drum. Fig. 3 is a cross-sectional view. Fig. 4 is a sectional view taken on line 4—4 of Fig. 1.

Reference now being had to the details 40 of the drawings by letter, A and B designate two semi-cylindrical sections of the drum, which together make up a cylinder, the circumference of which is composed of rods C, spaced apart slight distances. In 45 the drawings the ends of the sections, which are shown as solid, are provided with bearing recesses D at their meeting edges, and F designates lateral projections upon the ends of the section A, each projection having a 50 bearing aperture G for the shaft which rotates the drum. Guide projections, designated by letter H, extend beyond the inner straight edges of the ends of the section B and are adapted to have sliding contact with the opposite edges of the project-

ing portions upon the ends of the sections A, serving to guide the two sections as they are moved away or toward each other in a manner which will presently be described.

K is a cam shaft which is journaled in 60 apertures in the projections F and the cam shaft is provided with circumferential slots I, the bottoms of which slots are so shaped as to form cams and the ends of the section B are provided with recesses O, the upper marginal edges of which are concaved and adapted to engage and rest upon the cam bottoms of said grooves or slots, so that, when a rocking movement is imparted to the shaft K, the section B will be caused to raise 70 and lower, forming an expanding means for the two sections. Each of said apertures O has its portion adjacent to the inner edge of the ends of the sections in which they are formed laterally recessed as at O' to receive 75 a plate Q which may be readily removed should it be desired to remove the shaft K for any purpose.

A crank L has a hollow hub portion which is mounted upon the shaft K and said shaft 80 has a hollow end, the wall of which is interiorly threaded as at T which threads are engaged by the threads of the screw S, the inner end of the latter being tapered as at S'. The wall of the hollow portion of the 85 shaft has a hole leading from the interior thereof through its circumference and a pin W is mounted in said hole and has its inner end tapering and is disposed in the path of the inclined tapering end of said screw. 90 Said screw is adapted, when turned in one direction, to contact with the tapering end of the pin W and cause the outer end of the latter to frictionally engage the inner circumference of the hub of the crank L and 95 serve as a means for securely locking the same upon the shaft K. Said crank, it will be noted, has a series of markings M thereon, forming indicating means whereby the crank may be held in different positions 100 upon the shaft for the purpose of expanding the drum to different diameters as may be desired. A hollow handle X is fastened to said crank and carries a spring-pressed pin adapted to engage a recess in the end of one 105 of the sections to hold the crank in adjusted position, the pin, which is spring-actuated, being easily retracted within the handle by pressure thereon when it is desired to move the crank. Pins, designated 110

by letter J, project from one end of the section B and are spaced apart, adapted to form stops to limit the rocking movement of the shaft K by said crank coming in contact with said pins.

A bar M connects the ends of the projecting portion F and is provided with gripper fingers M' between two of the rods, forming the circumference of the section B and is 10 provided for the purpose of engaging and holding upon the drum one end of the strip of paper or fiber from which the box is to be formed by being wound upon the cylinder.

15 The operation of my expanding drum for making body portions of fiber boxes is as follows:—One end of the sheet of paper or fiber from which the box is to be made is placed against the circumference of the drum with its edge underneath the fingers M'. The operator then, by swinging the crank and giving the shaft K a partial rotary movement, may cause the two sections of the drum to expand, which movement is 20 due to the cams upon the shaft K coming in contact with the edges of the bearings as shown and which movement will cause the end of the paper to be securely clamped and, after which, a rotary movement is imparted 25 to the cylinder to cause the sheet of paper to wind about the drum as many plies as may be desired, suitable adhesive material being applied to cause the folds of the paper to adhere to each other. After the proper 30 thickness of the body portion of the box has been formed, the rotary movement of the drum is stopped and the operator, by imparting a reverse rocking movement to the shaft K, may cause the two sections of the 35 drum to contact or return to their normal positions, thus allowing the body portion of 40

the box that has been formed to be readily removed from the cylinder or drum.

What I claim to be new is:—

1. An expanding drum for making cylindrical fiber boxes, made up of expanding sections, the circumferences of said sections being made up of rods spaced apart, means upon one of said sections coöperating with one of said rods on the other section to clamp 45 and hold the sheet of fiber to the cylindrical section, while the sheet winds about the drum as the latter is rotated.

2. A sectional expanding drum, the circumferences of which are formed of rods 50 spaced apart, one of said sections having projections thereon which are apertured, a shaft journaled in said apertures, said shaft having a cam thereon adapted to engage the other section to cause the two sections to expand as the shaft is rocked, and clamping means upon said projections coöperating with a rod upon an adjacent section to hold 55 the end of a sheet of paper while being wound about the drum.

3. A sectional expanding drum, the circumferences of which are formed of rods spaced apart, said sections having projections upon the ends thereof which slide in contact with each other to guide the sections of the drum as they are expanded and contracted, a rock shaft journaled in apertures in projections upon one section and having cams engaging the edges of apertures 70 in the other section, and means for rocking 75 the shaft.

In testimony whereof I hereunto affix my signature in presence of two witnesses.

SAMUEL L. HIRSHEY.
